UNITED STATES PATENT OFFICE.

JACOB CHRISTIAN HANSEN-ELLEHAMMER, OF COPENHAGEN, DENMARK.

AUTOMATIC VALVE MECHANISM.

1,384,462.

Specification of Letters Patent. Patented July 12, 1921.

Application filed April 15, 1919. Serial No. 290,245.

To all whom it may concern:

Be it known that I, JACOB CHRISTIAN HANSEN-ELLEHAMMER, a subject of the King of Denmark, residing at No. 147 Oresundsgade, Copenhagen, in the Kingdom of Denmark, have invented certain new and useful Improvements in Automatic Valve Mechanism, of which the following is a specification.

10 This invention refers to a device for regulating the admission of the driving means in steam engines, compressed air engines, and similar engines, and its object is to regulate this admission with essentially simpler means than the ordinary slide or other valve mechanism.

15 The invention consists in a device for conducting the driving means through a counter-valve constructed for measuring off automatically a predetermined quantity of the driving means. The working of this device will in the following be explained with reference to the drawing, which diagrammatically shows the valve in four different positions.

20 In the drawings,

Figure 1 is a diagrammatic view showing the piston in a low position and the valve and plunger down;

25 Fig. 2 is a similar view showing the piston partially raised and the plunger elevated;

Fig. 3 is a diagram illustrating the piston fully raised, the plunger elevated and the valve open, and

30 Fig. 4 is a similar view with the piston partially retired but with the valve still open and the plunger raised.

As the piston 7, during its upward course, approaches the dead point (see the short

40 arrow 8 in Fig. 2), the here described admission valve 11, disposed between the inlet 9 for the driving means and the cylinder 10, will be lifted a certain distance from its seat, owing to the fact that the valve 11

45 is provided with a member 12 lying in the course of the piston as the latter approaches the dead point. As soon as this first loosening of the valve 11 has taken place, and the pressures above and below the valve have

50 thereby become equalized, the valve will automatically be brought into the quite open position shown in Fig. 3, by means of a special, automatically working counteracting device described in detail in the following.

55 During the ensuing downward move-

ment of the piston (see the arrow 13 in Fig. 4), the driving means rushes into the cylinder until the working of the special counter-acting device is automatically caused to cease, after which the valve closes, and the admitted driving means expands.

In the shown example, the said counter-acting device consists in a spring 14 and a rod-shaped member 16 collaborating therewith. The spring 14, which is disposed in the hollow rod 15 of the valve, is placed between the bottom of said hollow rod 15 and a head on the rod-shaped member 16, the latter projecting through the valve and extending into the cylinder (see Figs. 1 and 4).

During the rising of the piston (see the arrow 17 in Fig. 1), the piston will, at a certain point of time, come into contact with the member 16, lift it, and still further compress the spring 14, while the pressure of the driving means will hold the valve 11 fast against its seat, thereby also holding the upper contact-point of the spring fast. But, as soon as the aforesaid first loosening of the valve 11 (see Fig. 2) and its consequent release from the pressure of the driving means has taken place, the spring 14 will bring the valve into the fully open position shown in Fig. 3, where it is stopped by striking against the member 18 serving as guide for the valve rod 15. During this process, the piston has been at, or approximately at, the dead point, and thus the driving means has been at rest, with the exception of the slight movement that may have taken place during the equalizing of the pressures in the inlet pipe 9 for the driving means and in the very small free space in the cylinder respectively.

During the ensuing downward movement of the piston (see the arrow 13 in Fig. 4), the driving means rushes into the cylinder, and the member 16, which together with the spring 14 holds the valve lifted, descends with the piston, but the valve remains open as long as the resistance of the spring is sufficient to counteract the tendency to close the valve owing to the rushing effect of the driving means. The closing does not take place until the piston, during its downward motion has nearly reached the same position as that shown in Fig. 1. During the descent of the piston from the position shown in Fig. 3 and beyond that shown in

Fig. 4, the valve will be held open by the member 16 during approximately the same length of time as that required for said member 16 to move, during the ascending 5 of the piston, from the position shown in Fig. 1 to that shown in Fig. 3, so that the time of admission of the driving means directly depends upon the time of action or length of this member. The member 16 10 will, so to speak, measure off the quantity of driving means which is each time introduced into the cylinder. When the said quantity is reached the admission of driving means is cut off and the expansion begins. 15 When the downward stroke of the piston is accomplished, and the steam or air has been exhausted in some way or other already known, and when the piston has again, during its ascent, reached the position shown 20 in Fig. 1, the aforesaid cycle of events will be automatically repeated, *id est*, first the compression of the spring 14, then the first loosening of the valve 11, and the valve's springing up into its wholly open position, at 25 the time that the piston is at its top position, and finally the regulating by the member 16 of the fresh quantity of driving means during the ensuing downward stroke.

I claim:—

30 1. In combination with an engine composed of a cylinder and a piston, of a chamber communicating with the cylinder and in connection with a source of supply of a driving medium, a valve for controlling the 35 communication between said chamber and cylinder and acted on by the engine to open a small degree when the piston approaches the dead center whereby to put the valve in a condition of balance acted upon equally 40 on both sides by the driving medium, and resilient means compressible by the engine as the piston approaches the dead point and connected to said valve whereby to cause the

opening of the latter to a predetermined degree.

45

2. In combination with an engine, of a chamber connected thereto and in communication with a source of driving medium supply, valve means controlling communication between said chamber and engine and adapted to be automatically opened by the engine, and resilient means adapted to be automatically compressed by the engine prior to the opening of said valve means and carried by the latter, said resilient means adapted to expand when pressure upon the valve means is equalized and open the latter to expose a predetermined port area.

50

3. In combination with an engine, of a chamber in connection therewith and having communication with a source of driving medium supply, a valve for controlling the communication between said chamber and engine and adapted to be held seated by the pressure within the chamber of the driving medium, said valve having a projection acted on by the engine to open the valve sufficiently to balance the pressure thereon, a hollow valve stem carried by the valve, a guide therefor, a plunger in the valve 70 stem, spring means in the stem adapted to be put under compression by the plunger, said spring means adapted to expand following compression of the same whereby to open the valve through its hollow stem to a 75 predetermined degree, and a rod on the plunger acted on by the engine to cause compression of the spring means.

60

In testimony, that I claim the foregoing as my invention, I have signed my name 80 in presence of two subscribing witnesses.

65

JACOB CHRISTIAN HANSEN-ELLEHAMMER.
